CLAIM

The ornamental design for a flat panel display stand, as shown and described.

DESCRIPTION

FIG. 1 is a front perspective view of a flat panel display stand embodying our novel design;

FIG. 2 is a rear perspective view of a flat panel display stand embodying our novel design;

FIG. 3 is a left side elevational view of the flat panel display stand of FIG. 1;

FIG. 4 is a front elevational view of the flat panel display stand of FIG. 1;

FIG. 5 is a right side elevational view of the flat panel display stand of FIG. 1;

FIG. 6 is a rear elevational view of the flat panel display stand of FIG. 1;

FIG. 7 is a top plan view of the flat panel display stand of FIG. 1;

FIG. 8 is a bottom plan view of the flat panel display stand of FIG. 1; and,

FIG. 9 is a front elevational view of the flat panel display stand of FIG. 1 connected to support a flat panel display.

The broken lines shown in the drawings are for illustrative purposes only and form no part of the claimed design.
